(57) **CLAIM**

The ornamental design for a slat as shown and described.

DESCRIPTION

FIG. 1 is a front, upper, right perspective view of a slat of our new design;

FIG. 2 is a rear, lower, left perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

Broken lines of equal length (e.g., dash-dash) represent unclaimed subject matter and form no part of the claimed design. Broken lines of unequal length (e.g., dash-dot) define bounds of the claimed subject matter and form no part of the claimed design.
